DOLL VOICE AND MOUNTING FOR SAME

John H. Wilhelm, Hamilton Beach, N. Y., assignor
to Voices, Incorporated, New York, N. Y., a cor-
poration of Delaware

Application February 5, 1935, Serial No. 5,024

23 Claims. (Cl. 46—183)

This invention relates to toys, and more particularly to dolls provided with a sound producing device, as well as to sound producing devices therefor.

5 Dolls provided with sound producing devices have ordinarily been of the stuffed type, the body being fabric filled with a suitable filler which is removed at the center near the back to make room for the so-called voice. The voice, 10 whether of the crier or articulative or "mama" type, is commonly made cylindrical with a cap at one end provided with numerous holes for sound discharge. This cap is disposed at the back of the doll and is concealed by the fabric 15 covering the doll body. The stuffing of the doll body effectively holds the voice in place. Dolls having hollow bodies are popular, especially those made of rubber, but have not heretofore been provided with voices because of the 20 difficulty of securely mounting a voice within a hollow body. Furthermore, the trend in manufacture is toward the production of realistic dolls which may be undressed and dressed, and it is therefore objectionable to disfigure the body 25 with a large circular opening in the back exposing the end of a voice itself perforated with numerous sound discharge openings. The primary object of my invention is to overcome the foregoing difficulties and to provide a practical 30 inexpensive secure mounting for a voice within a hollow doll body while requiring only a single small discharge hole which may, if desired, be located at the navel of the body.

Further objects of my invention are to improve the voice or sound producing device per se 35 with a view to obtaining a loud concentrated sound discharge of substantially constant volume. Still further objects are to facilitate mounting of the voice in a doll body so that the voice may 40 be mounted on either a half or a whole body; to make unnecessary the use of machinery other than a simple hand punch; and to effectively prevent injury to the voice during the mounting operation.

45 Still another object of my invention resides in the provision of a flexible doll having a voice capable of dual operation, the voice being actuated either gravitationally or by compression of the flexible body, all without in any way increasing the complexity of the voice.

To the accomplishment of the foregoing and other objects which will hereinafter appear, my invention consists in the voice and doll body elements and their relation one to the other as 50 hereinafter are more particularly described in

the specification and sought to be defined in the claims. The specification is accompanied by drawings in which:

Fig. 1 is a horizontal section taken through a hollow doll body with a voice mounted therein; 5

Fig. 2 is a front elevation of the sound discharge opening;

Fig. 3 is a section through a modified voice mounted at the back of a doll body;

Fig. 4 is a similar voice arranged for mounting at the front of a doll body; 10

Fig. 5 is a section through an articulative voice mounted at the back of a doll body;

Fig. 6 is a similar voice mounted at the front 15 of a rubber body;

Fig. 7 is a section through a preferred form of voice mounted in a hollow rigid body;

Fig. 8 is a modification showing the application 20 of the same voice to a flexible rubber body;

Fig. 9 illustrates the method of mounting the voice in a half doll body;

Fig. 10 illustrates the method of mounting the voice in a whole doll body;

Figs. 11 and 12 are explanatory of the dual 25 operation of the voice when mounted in a substantially imperforate flexible body; and

Fig. 13 is a modification of the voice shown in 30 Fig. 7.

Referring to the drawings, the invention comprises a voice generally designated V and having at one end a cap C provided with an outwardly projecting tubular sound passage T. The voice is mounted in a body B having an opening O dimensioned to receive the tubular sound 35 passage T the outer end of which is flanged outwardly to hold the voice in place.

Referring more particularly to Figs. 1 and 2, the voice comprises a preferably cardboard cylindrical casing wall 12 protectively housing a preferably frustro-conically shaped flexible bellows cloth 14. The small end of the bellows is closed by an imperforate weighty head 16 made in the present instance of a heavy inner member 18 and a flanged sheet metal cover plate 20, 40 the end of the bellows being received and tightly clamped between weight 18 and cover plate 20. The large end of the bellows is closed by a cap 22 which serves also to close the end of casing wall 12 and to secure the bellows to the casing. The opposite end of the casing may be closed by 45 a suitable cap 24 perforated as, for example, at 26, in order to provide communication between the space surrounding the bellows and the relatively large chamber within the doll body.

The closure 22 is preferably stepped, as is indi- 50 55

cated at 28, in order to form the outer part of a sound box 30 the inner part of which is defined by a flanged disc 32. Disc 32 is incised and appropriately deformed at 34 to receive a reed 5 assembly R. This assembly is of conventional type comprising a vibratile reed 36, an adjacent channel member 38, and a clip 40 securing the stationary end of the reed to the channel member. As will be understood by those skilled in 10 the art, the reed assembly R is sealed in disc 32, as by the use of wax. It will also be understood that air expelled from the bellows when the voice is inverted and head 16 descends, is forced through the reed assembly R, thereby producing 15 a crying sound which passes from the chamber 30 out of the doll through the tubular sound passage T.

In the present case, the tubular passage T is formed integrally with the cap 22, and the 20 voice is secured on the wall of the body by flanging the end of the tube outwardly, as is indicated at 42. This may be accomplished by appropriate means such as a spinning machine, while holding the voice in the front half 44 of the doll 25 body and before cementing the front half 44 to the back half 46 of the body.

It should be noted that contrary to conventional practice, the sound producing reed is mounted at the fixed end of the voice instead of 30 being mounted on the movable weighty head 16. This change in construction brings and maintains the reed assembly R immediately adjacent to the sound discharge opening, thus increasing the volume of sound actually heard outside the doll.

35 Referring now to Fig. 3, I show the upper part of a voice V the lower part of which is identical with that shown in Fig. 1. The upper part differs in that the channel 50 for the reed assembly R is formed integrally with a closure disc or plate 52 40 which extends entirely across the end of the voice. The reed 54 is secured to plate 52 by a rivet 56. A sound chamber 58 is provided by means of an outer cap 60 flanged over the end of the voice at 62. Cap 60 is in the present instance 45 provided with two tubular sound passages, and these passages take the form of eyelets 66 made separately from cap 60 and subsequently applied thereto. Eyelets 66 pass through mating holes in the doll body and are flanged outwardly at 68 50 to lock the voice in place. In the present case the voice is secured to the rear rather than the front wall of the doll body, and the object is to minimize the size and conspicuousness of the eyelets rather than to simulate a specific body 55 opening.

In Fig. 4 I show a similar voice modified for mounting on the front wall of the doll body at the naval opening. To this end, only cap C need be changed, it being provided with a single eyelet 60 70 which is flanged outwardly at 72. In the present case I also illustrate how eyelet 70 may be stepped, as is indicated at 74, thereby providing a surface opposed to flange 72 for locking the eyelet securely in place without straining the parts 65 of the voice, and at the same time providing clearance at 76 to compensate for the convex curvature of the front of the doll body.

70 In Fig. 5 I illustrate how some features of my invention may be applied to an articulative or so-called "mama" voice. This voice is similar to the crier in comprising a cylindrical casing wall 80 protectively housing a flexible bellows 82 closed at its inner end by a movable weighty head 84 and at its outer end by a cap 86. Sound is produced 75 by a reed assembly R mounted in a valve tube 88

extending between cap 86 and a cap 90 at the opposite end of the casing. Air compressed in the bellows passes through a passage 92 at the lower end of tube 88 and thence through reed assembly R, thereby producing a tone. 5

The head 84 is initially at the top of tube 88, and the passage of sound from tube 88 is greatly constricted, it taking place only through the relatively tiny opening 94 provided at the top end of the tube. When the inner part 96 of head 84 10 passes the slot 98 extending peripherally around tube 88, sound is very freely discharged between the inner and outer parts 96 and 84 of the head and thence through holes 99. When the outer part 84 of the head reaches slot 98, the discharge 15 of sound is again restricted to the tiny opening 94. Then, when the outer part 84 of the head falls below slot 98, the sound is freely discharged through slot 98. These successive steps in the 20 operation of the voice correspond to the consonant and vowel sounds in the word "mama".

The thus-modulated sound is discharged through tubular sound passages here formed by eyelets 100 connected at their inner ends to the 25 cap 90 and flanged at their outer ends over the body wall. In the present species of the invention, like that shown in Fig. 3, the voice is mounted on the back rather than the front of the body.

In Fig. 6 I illustrate a substantially similar "mama" voice mounted on the front wall of a doll body. For this purpose, a single eyelet 102 is 30 employed, the eyelet preferably being enlarged at 104 and secured to the cap or closure 106 of the voice, as by the use of appropriate tongue and slot connections 108. The cap 106 is perforated 35 to form sound discharge holes 110 located within the enlargement 104 of the eyelet. In this manner the sound from the voice is confined and directed through the tubular sound discharge passage. 40

In this figure I may direct attention to the preferably counter-sunk washer 112 over which eyelet 102 is flanged at 114. I consider the use of such a washer desirable when mounting the voice on a flexible rubber body. I may also direct attention to the annular wall 116 molded on the interior of the body, which forms a cup or recess receiving and supporting the body of the voice. This additional support for the voice may be provided in connection with any of the arrangements 45 herein disclosed, but from my experience is needed if at all only in connection with articulative voices which ordinarily are larger and heavier than simple "criers". 50

A form of my invention having special advantages is illustrated in Fig. 7 in which it will be seen that the voice, like that shown in Fig. 1, comprises a cylindrical casing wall 12 protectively housing a flexible bellows 14 the movable end of which is closed by an imperforate weighty head 16 including an inner weight 18 and a sheet metal cover plate 20. The lower end of cylinder 12 is closed by a cap 120, while the upper end is closed by cap C which here is centrally apertured at 122. The tubular sound discharge member T is a separate tubular element which passes through cap C and projects inwardly therefrom a substantial distance, as is indicated at 124. The lower end of the tube is closed, preferably by the use of a small closure 126. The tube is beaded outwardly at 128 just inside cap C. This bead takes the voice load when the tube is mounted in the body by flanging its outer end outwardly, as is indicated at 130. 65

The reed assembly R is conventional but is 70 75

mounted on the voice by passing the same through an opening in the side wall of tube 124 inside of cap C, as is clearly shown in the drawings. The fit between tube 124 and closure 126 and the cap C is made airtight, and the opening around the reed assembly R is waxed or otherwise treated to the same end.

While the weighty head 16 of the bellows is imperforate and substantially leak-proof in operation, the cover plate 20 thereof is preferably apertured at 132 in alignment with tube 124. The cap 120 is similarly apertured at 134.

The reason for this construction will be evident from consideration of Fig. 9 in which I illustrate how the voice is mounted in a half doll body 136. Tubular projection T in unflanged condition is inserted through the navel opening 136 of the doll, and the voice and half body are slipped over a support rod or anvil 138 projecting upwardly from a suitable base 140. Rod 138 passes through apertures 132 and 134 and bears directly on the lower side of weight 18 the upper side of which in turn bears against the end closure 126 of the sound discharge tube. It will be noted in Fig. 9 that the internal projection 124 of the tube is so dimensioned that the tube is directly supported by rod 138, while the head 16 of the bellows still has at least a little clearance for further movement. The outer end of the tube is then curled or flanged outwardly by using a simple curling punch 142 having an appropriately shaped end 144. This punch may be operated by a press or simply hit with a hammer, and the reaction to the flanging pressure is taken directly by support rod 138 without any possibility of injury to the working parts of the voice. This ability to support the tube against a direct axial blow makes unnecessary the use of spinning machinery or other complicated mechanism for providing the flange 130 on the outer end of the tube.

If the body is a rigid pulp body, the mating back half is next cemented to the front half, after which the body may be sized and appropriately painted by dipping or spraying. At this time it is desirable to protect the voice, and it may be sealed in a very simple manner by inserting a cork or stopper 146 of appropriate size in the navel opening or sound discharge tube, as is illustrated in Fig. 7. It will be understood that the sound discharge tubes in the various forms of the invention heretofore described may be similarly stopped during sizing or painting of the doll body.

When mounting the voice in a soft rubber body, I consider it desirable to enlarge the effective area of the flange at the outer end of the sound discharge tube by using a suitable washer. This feature is illustrated in Fig. 8 which is a fragmentary view similar to that shown in Fig. 7 except that the wall 148 of the doll body is made of rubber and a preferably flanged washer 150 is inserted around tube T from the outside of the body before the tube is flanged outwardly at 152.

Rubber bodies are sometimes molded in one piece instead of separate front and back halves. The manner in which the voice may be applied to such a body is illustrated in Fig. 10 in which I show a soft rubber body 154 having a neck opening 156 large enough or sufficiently expansible to receive the voice V. The voice is supported on a rod or anvil 158 mounted at the inner end of a rigid support arm 160 which passes through neck opening 156 during the mounting operation. The voice is mounted just as heretofore described, the outer end of the sound discharge tube being

curled or flanged outwardly by a suitable curling punch 142.

Although the rubber doll body has relatively large openings or sockets 162 and 164 to receive arms and legs, as well as the neck opening 156 which receives the doll head, the body when completed is substantially imperforate. This fact makes it possible to operate the voice not only by gravity but also by compression of the doll body. Referring to Fig. 11, it will be noted that the arms 10 and legs have ball-shaped ends 166 and 168 and are held in the doll by appropriate resilient means 170. The head 172 is similarly fitted in the neck opening 156, and the elastic nature of the parts results in a substantially airtight fit, 15 at least as against sudden compression of the body. When the body is compressed, deforming the same from the shape shown in broken lines at 174 to that shown in solid lines at 174', the increased pressure is freely transmitted from the 20 body to the voice chamber surrounding the bellows, and the head 16 is therefore elevated. In other words, the atmospheric pressure transmitted from outside the doll body to the inside of the bellows is less than the pressure surrounding the bellows, and the latter is accordingly compressed, thus actuating the voice.

In Fig. 12 I show the rubber doll body arranged face downwardly. When first placed in this position the voice is, of course, actuated gravitationally and head 16 then remains at the bottom of the casing. If the body is compressed from the solid line position 176 to the dotted line position 176' and then suddenly released, the head 16 is drawn upwardly. It thereupon again sinks to 35 lowermost position, thereby actuating the voice. It will be understood that the doll body is not truly leak-proof but is merely sufficiently tight to cause a response to sudden changes in volume. The body if truly leak-proof might tend to excessively damp the gravitational operation of the voice.

Referring now to Fig. 13, I show a voice very similar to that illustrated in Fig. 7 but modified by reversing the bellows. This voice, like that previously described, comprises a preferably cardboard cylindrical casing 12 protectively housing a flexible bellows 14 actuated by a weighty head 16. In the present case, however, the stationary end of bellows cloth 14 is attached to the casing at the end remote from the sound discharge opening by means of a cap 180. This cap is apertured at 182 to vent the interior of the bellows and to receive the anvil or support rod heretofore described. The assembly of the cap C, tube T, and sound producing reed R is just like that heretofore described, but in the present case the cap C is secured directly to the upper or sound discharge end of cylindrical casing 12 without the interposition of bellows cloth. The weighty head 16 may be made as heretofore described, by assembling an imperforate inner weight member 18 and a sheet metal cover plate 184. Cover plate 184 is depressed at 186 to clear the inner end or cap 126 of sound discharge tube T.

In operation, the weight falls very freely, and this is probably due to the fact that air is compressed outside the bellows rather than inside the bellows, which helps keep the weight freely centered and away from the casing wall during movement.

It is believed that the mode of constructing and using my invention, as well as the many advantages thereof, will be apparent from the foregoing detailed description. The invention makes 75

it possible to mount a doll voice in a hollow toy or doll body without disfiguring the body and without impeding the sound discharge. The mounting is provided in a simple and inexpensive manner and is sufficiently strong to withstand abuse of the doll. The voice itself is improved, the sound emitted being loud and distinct, and this, I believe, is due largely to the fact that the reed assembly is stationarily located immediately at the sound discharge opening instead of being mounted on the movable weight in which case it is remote from the sound discharge opening for at least part of the operating period. In the preferred form of voice illustrated in Fig. 7, the sound is probably further concentrated because of the mounting of the reed assembly directly in a discharge tube of small dimension. The voice is readily mounted not only in a half body but also in a whole body, and in preferred form the outer end of the sound discharge tube may be solidly curled or flanged outwardly without using spinning or like machinery. The internal construction of the voice is such that injury to the voice during the mounting operation is effectually guarded against. When mounted in a substantially imperforate flexible rubber body, the voice is capable of dual operation either gravitationally or by compression of the doll body.

It will be apparent that while I have shown and described my invention in preferred forms, many changes and modifications may be made in the structures disclosed, without departing from the spirit of the invention, defined in the following claims.

35. I claim:

1. A toy voice comprising a casing, a flexible bellows therein, an imperforate weighty head secured to one end of said bellows, a first cap at the other end of the bellows and one end of the casing, a second cap at the other end of the casing, and a sound producing element mounted on one of said caps.

2. A toy voice comprising a casing, a flexible bellows therein, an imperforate weighty head secured to one end of said bellows, a first cap at the other end of the bellows and one end of the casing, a second cap at the other end of the casing, a sound producing element mounted on one of said caps, and means on said cap for mounting the voice on the wall of a doll body.

3. A toy voice comprising a cylindrical casing wall, a frusto-conical flexible bellows therein, an imperforate weighty head secured to and closing the small end of said bellows, a first cap at the large end of the bellows and one end of the cylindrical casing wall, a second cap at the other end of the casing, a sound producing element mounted on one of said caps, and a sound discharge passage leading from said element through the cap on which it is mounted.

4. A doll voice comprising a cylindrical casing wall, a frusto-conical flexible bellows therein, an imperforate weighty head secured to and closing the small end of said bellows, a first cap closing the large end of the bellows and one end of the cylindrical casing wall and securing the large end of the bellows thereto, a second cap at the other end of the casing, a sound producing element mounted on one of said caps, a sound discharge passage leading from said element through the cap, and means on said cap for mounting the voice on the wall of a doll body.

5. A toy voice comprising a casing, a flexible bellows therein, a weighty head secured to and closing one end of said bellows, a first cap clos-

ing the other end of the bellows and one end of the casing, a second cap at the other end of the casing, a sound discharge tube passing through one of said caps, means closing the inner end of said tube, and a reed assembly mounted on the tube within said casing.

6. A toy voice comprising a cylindrical casing wall, a frusto-conical flexible bellows therein, a weighty head secured to and closing the small end of said bellows, a first cap closing the large end of the bellows and one end of the cylindrical casing wall and securing the large end of the bellows thereto, a second cap at the other end of the casing, a sound discharge tube passing through and secured to one of said caps, means closing the inner end of said tube, and a sound producing reed with adjacent channel member passing through and mounted on the side wall of said tube within said casing.

7. A doll having a hollow body with a hole therein, and a voice in said body comprising a casing, a flexible bellows therein, a weighty head secured to and closing one end of said bellows, a first cap closing one end of the casing and securing the other end of the bellows thereto, a second cap at the other end of the casing, a sound producing reed mounted near one of said caps, and a tubular sound passage projecting outwardly from said latter cap through the hole in the body and serving to hold the voice in place.

8. A doll having a hollow body with a hole therein, and a voice in said body comprising a casing, a flexible bellows therein, a weighty head secured to and closing one end of said bellows, a first cap closing one end of the casing and securing the other end of the bellows thereto, a second cap at the other end of the casing, a sound discharge tube passing through and secured to one of said caps, means closing the inner end of said tube, and a sound producing reed mounted on said tube within said casing, the outer end of said tube passing through the hole in the body and being flanged outwardly to hold the voice in place.

9. A doll having a hollow body with a hole at the navel thereof, and a voice in said body comprising a cylindrical casing wall, a frusto-conical flexible bellows therein, a weighty head secured to and closing the small end of said bellows, a first cap closing one end of the cylindrical casing wall and securing the large end of the bellows thereto, a second cap at the other end of the casing, a sound discharge tube passing through and secured to one of said caps, means closing the inner end of said tube, and a sound producing reed and adjacent channel member passing through and mounted on the wall of said tube within said casing, the outer end of said tube passing through the navel opening of the body and being flanged outwardly to hold the voice in place in the body.

10. A doll having a hollow body with a hole at the navel thereof, and a voice in said body comprising a casing, a flexible bellows therein, a weighty head secured to and closing one end of said bellows, a first cap closing one end of the cylindrical casing wall and securing one end of the bellows thereto, a second cap at the other end of the casing, a sound discharge tube on one of said caps, and a sound producing reed assembly mounted near said second cap, the outer end of said tube passing through the navel opening of the body and being flanged outwardly to hold the voice in place in the body.

11. A doll having a hollow flexible rubber body

with a hole at the navel thereof, and a voice in said body comprising a casing, a flexible bellows therein, a weighty head secured to and closing one end of said bellows, a sheet metal cap closing one end of the cylindrical casing wall and securing one end of the bellows thereto, a sound discharge tube on said cap, and a sound producing reed assembly mounted on said cap, the outer end of said tube passing through the navel opening of the body and being flanged outwardly to hold the voice in place in the body.

12. A toy voice comprising a casing, a flexible bellows therein, a weighty head secured to one end of said bellows, a sheet metal cap closing one end of the casing, a sound discharge tube passing through and secured to said cap, means closing the inner end of said tube, a sound producing reed assembly mounted on the side wall of said tube within said cap, and a second cap closing the opposite end of the casing, said last-named cap being cut away in alignment with the aforesaid tube.

13. A doll crier comprising a cylindrical casing wall, a frusto-conical flexible bellows therein, an imperforate weighty head secured to and closing the small end of said bellows, said head including a heavy metallic member within the bellows and a thin sheet metal cover plate outside the bellows, the small end of the bellows being received and clamped between said member and cover plate, a first cap closing one end of the cylindrical casing wall and securing the large end of the bellows thereto, a second cap at the other end of the casing, a sound discharge tube passing through one of said caps, and a sound producing reed and adjacent channel member leading into said tube within said casing.

14. A doll voice comprising a casing, a flexible bellows therein, an imperforate weighty head secured to and closing one end of said bellows, said head including a heavy metallic member within the bellows and a thin sheet metal cover plate outside the bellows, the end of the bellows being received and clamped between said member and cover plate, a sheet metal cap at one end of the casing, a sound discharge tube passing through and secured to said cap, means closing the inner end of said tube, and a sound producing reed and adjacent channel member passing through and mounted on the side wall of said tube within said cap, a cap closing the opposite end of the casing, said last-named cap being apertured in axial alignment with the aforesaid tube.

15. A doll having a hollow body with a hole therein, and a voice in said body comprising a casing, a flexible bellows therein, a weighty head secured to and closing one end of said bellows, a sheet metal cap closing one end of the casing, a sound discharge tube passing through and secured to said cap, sound producing means, and a cap closing the opposite end of the casing, said last-named cap being perforated in alignment with the aforesaid tube, said sound discharge tube passing through the body hole and serving to hold the voice in place.

16. A doll having a hollow body with a hole therein, and a voice in said body comprising a cylindrical casing wall, a frusto-conical flexible bellows therein, a weighty head secured to and closing the small end of said bellows, said head including two mating metallic members, the small end of the bellows being received and clamped between said members, a first cap closing one

end of the cylindrical casing wall and securing the large end of the bellows thereto, a second cap at the other end of the casing, an unobstructed sound discharge tube having its outer end projecting outwardly from one of said caps and its inner end passing through and strongly secured to said cap, and sound producing means, the outer end of said sound discharge tube passing through the body hole and serving first, to hold the voice in place, and second, as the regular sound discharge passage of the voice.

17. A doll having a hollow body with a hole at the navel, and a voice in said body comprising a casing, a flexible bellows therein, an imperforate weighty head secured to and closing the small end of said bellows, said head including a heavy metallic member within the bellows and a thin sheet metal cover plate outside the bellows, the end of the bellows being received and clamped between said member and cover plate, a first cap closing one end of the casing, a sound discharge tube passing through said cap, sound producing means at the side of said tube within said casing, and a second cap closing the opposite end of the casing, said last-named cap being apertured in axial alignment with the aforesaid tube, said sound discharge tube passing through the body hole and serving to hold the voice in place.

18. The method of mounting in a hollow doll body having an opening, a voice comprising a casing having a cap at one end with a tubular sound discharge member passing through said cap and closed at its inner end but open at its outer end, an apertured cap at its opposite end, and a bellows with a weighty head movable within said casing, which includes the steps of passing the outer end of the tubular sound discharge element through the opening, passing a support member through the apertured cap and thereby bringing the weighty head against the inner end of the sound discharge tube in order to support the same, and then flanging the outer end of the tube outwardly against the outside of the body wall, the reaction of said flanging force being taken by the aforesaid support member.

19. A toy voice comprising a casing having a sheet metal cap at the sound discharge end thereof, a sound producing reed mounted on said cap, a bellows with an imperforate weighty movable head at one end thereof, and an apertured cap at the other end of the bellows securing the same to the other end of the casing.

20. A toy voice comprising a casing having a sheet metal cap at the sound discharge end thereof, said cap having a tubular sound discharge member projecting outwardly therefrom and adapted to pass through a doll body opening and to hold the voice in place, a sound producing reed mounted at the sound discharge end of the voice, a bellows with a weighty movable head at one end thereof, and an apertured cap securing the other end of the bellows to the other end of the casing.

21. A toy voice comprising a cylindrical casing wall, a frusto-conical flexible bellows therein, a weighty head secured to and closing the small end of the bellows, an apertured sheet metal cap closing the large end of the bellows and securing the same to one end of the cylindrical casing, a sheet metal cap closing the other end of the casing, a sound discharge tube passing through and secured to said cap, means closing the inner end of said tube, and a sound producing reed with

adjacent channel member passing through and mounted on the side wall of said tube within said cap.

22. A doll voice comprising a casing, a flexible bellows therein, an imperforate weighty head secured to and closing one end of said bellows, said head including a heavy metallic member within the bellows and a thin sheet metal cover plate outside the bellows, the end of the bellows being received and clamped between said member and cover plate, a first sheet metal cap securing the opposite end of the bellows to one end of the casing, a second sheet metal cap at the other end of the casing, a sound discharge tube passing through and secured to the latter cap, means closing the inner end of said tube, and a sound producing reed and adjacent channel member passing through and mounted on the side wall of said tube within said cap, the first-mentioned

cap being apertured in axial alignment with the aforesaid tube.

23. The combination with a hollow flexible rubber doll body having an opening at the navel but being otherwise substantially imperforate, of a voice comprising a perforate casing having a cap at one end with an unobstructed tubular sound discharge member, a bellows with a movable weighty head within said casing, said tubular sound discharge member being strongly secured to the cap and passing through the aforesaid navel opening and being flanged outwardly to hold the voice in place, said voice being operable either gravitationally, because of the weighty head, or by compression and release of the flexible rubber body because of the communication between the body and bellows through the perforate casing.

JOHN H. WILHELM.
